(57) **CLAIM**

The ornamental design for an image display device, as shown.

DESCRIPTION

FIG. 1 is an exploded perspective view of an image display device showing my new design;

FIG. 2 is a front perspective view thereof;

FIG. 3 is a rear perspective view thereof;

FIG. 4 is a front view thereof;

FIG. 5 is a rear view thereof; and,

FIG. 6 is a side view.

The design is the shape and configuration of an image display device having a generally cylindrical body and an attachable backing portion.
